UNITED STATES PATENT OFFICE.

CHARLES W. HULLINGS, OF PHILADELPHIA, PENNSYLVANIA, ASSIGNOR OF ONE-HALF TO JESSE W. THATCHER, OF PHILADELPHIA, PENNSYLVANIA.

STEAM-BOILER FIRE-BOX.

No. 811,401.

Specification of Letters Patent.

Patented Jan. 30, 1906.

Application filed June 24, 1905. Serial No. 266,905.

To all whom it may concern:

Be it known that I, CHARLES W. HULLINGS, a citizen of the United States, and a resident of Philadelphia, in the county of Philadelphia and State of Pennsylvania, have made a certain new and useful Invention in Steam-Boiler Fire-Boxes; and I declare the following to be a full, clear, and exact description of the same, such as will enable others skilled in the art to which it appertains to make and use the invention, reference being had to the accompanying drawings, and to letters of reference marked thereon, which form a part of this specification.

15 Figure 1 is a central longitudinal vertical section of my invention as applied. Fig. 2 is a section on the line 2 2, Fig. 1. Fig. 3 is a sectional detail view of the connection of baffle-plate and stay-tubes. Fig. 4 is a perspective detail view of a section of the baffle-plate.

The invention has relation to steam-boiler fire-boxes, and particularly to improvements upon the devices shown in Letters Patent No. 25 490,629 and No. 495,939; and the invention consists in the novel construction and combinations of parts, as hereinafter set forth.

The object of the present invention is to make provision for more perfect combustion 30 in order to effect a reduction of cinder and carbon particles in the fire-box and also to arrange for a better circulation of the boiling water.

In the accompanying drawings, illustrating the invention, the letter *a* designates the furnace or fire-box, and *b* the boiler having extensions *c*. Flues for the passage of the products of combustion to the stack are indicated at *d*. The doorway of the fire-box is 40 shown at *e*, and *f* represents grate-bars.

The deflector is shown at *g* and is preferably of transversely-arched form, located below the crown-sheet *k* and extending backward from the front sheet of the fire-box 45 about two-thirds the length of said fire-box, where it terminates in an upwardly-arched marginal portion. Under the back portion of the deflector is located the baffle-plate *m*, which is also transversely arched in order that 50 it shall have approximate parallel position to the deflector. The baffle-plate may be made hollow and in sections engaging each other by tenon-and-groove joints, as shown. The baffle-plate may be loose from the fire-

box walls at its ends and may be held in position by means of securing-flanges *p* at the back fire-box sheet and by means of upright stay-tubes *s* to the crown-sheet, as shown. The stay-tubes are designed to promote circulation of the boiler-water through the baffle-plate tubes and boiler extensions. 55

The baffle-plate extends under the back of the deflector and past its marginal end in such wise as to provide the passage or throat *t*, which is of transversely-arched or approximately arched form. This passage, lying between the concave bottom of the deflector and the convex top of the baffle-plate, is of arched form and of approximately equal vertical depth at the sides as well as in its 70 middle portion. This passage *t* is of comparatively small depth with relation to its transverse extent and has for its top the back portion of the deflector and for its bottom the front portion of the baffle-plate. 75

The hollow sections of the baffle-plate may be strengthened by means of the columns *u*. The walls of the baffle-plate in front and rear are provided with apertures for the pipes *r* and *p'*, which form means of 80 communication with the extension-chambers of the boiler.

All the products of combustion are designed to pass through the transverse passage *t*, in all parts of which said products, including cinders and unburned particles of carbon, are subjected to intense heat, whereby they are designed to be thoroughly consumed, so that the products of combustion 85 passing through the flues *d* to the stack are relieved of such cinders and carbon particles and are reduced practically to the condition 90 of gas and vapor. The parallel or approximate parallelism of the deflector to the baffle-plate is designed to provide a passage 95 wherein the draft tends to concentrate the flames and heat in an equalized manner at all points from side to side, so that the cinders cannot escape their effective action. In the 100 patents hereinbefore referred to the lateral portions of the passage are of large capacity compared with the middle portion and tend to allow the cinders to pass unconsumed to the stack.

The circulation of water from the boiler in 105 and through the baffle-plate is designed to be efficient because of the hollow stay-pipes leading to the boiler extension above the

crown-sheet, and proper bracing and support of the baffler-plate is secured by these pipes, which because of the water circulating through them are conditioned to withstand 5 the great heat of the flames in the passage or throat *t*.

Having described the invention, what I claim, and desire to secure by Letters Patent, is—

- 10 1. In a boiler fire-box, the combination with a deflector extending backward from the front wall of the fire-box, of a forward-extending baffler-plate transversely and longitudinally parallel to said deflector, and extending from the back wall of the fire-box under the back portion of the deflector, whereby a transversely-equalized passage is formed between such deflector and baffler-plate, substantially as specified.
- 15 2. In a boiler fire-box, the combination with a transversely-arched deflector extending backward from the front wall of the fire-box, of a forward-extending transversely-arched baffler-plate, extending from the back wall of the fire-box under the back portion of the deflector and parallel thereto, to form a

combustion-passage, substantially as specified.

3. In a boiler fire-box, the combination with a deflector extending from the front 30 wall of the fire-box, of a hollow baffler-plate parallel to said deflector, and upright circulating-pipes connecting and supporting the baffler-plate in position, substantially as specified.

35 4. In a boiler fire-box, the combination with a deflector extending from the front wall of the fire-box, of a baffler-plate extending from the rear wall of the fire-box beyond the end of said deflector and parallel thereto 40 both in longitudinal and in transverse relation, whereby is provided, between said deflector and baffler-plate, a flame-passage of approximately equalized draft from side to side, substantially as specified.

45 In testimony whereof I affix my signature in presence of two witnesses.

CHARLES W. HULLINGS.
